UNITED STATES PATENT OFFICE.

EDWIN B. ADAMS, OF MARION, INDIANA, ASSIGNOR TO D. C. JENKINS GLASS COMPANY, OF KOKOMO, INDIANA, A CORPORATION.

DESIGN FOR A BOWL OR SIMILAR ARTICLE.

Application filed February 4, 1924. Serial No. 8,530. Term of patent 3½ years.

To all whom it may concern:

Be it known that I, EDWIN B. ADAMS, a citizen of the United States of America, residing at No. 2213 S. Adams Street, in the city of Marion, county of Grant, and State of Indiana, have invented a new, original, and ornamental Design for a Bowl or Similar Article, of which the following is a specification, reference being had to the accompanying drawings, forming a part thereof.

In the drawings, there is shown a side elevation of a bowl showing my new design applied thereto.

I claim:

The ornamental design for a bowl or similar article, as shown.

EDWIN B. ADAMS.
